UNITED STATES PATENT OFFICE.

ALEXIS LE BLANC, OF NEW YORK, N. Y., ASSIGNOR TO COMPOSITE METAL LATH COMPANY, OF NEW YORK, N. Y., A CORPORATION OF NEW YORK.

LOOM.

1,379,194.

Specification of Letters Patent. Patented May 24, 1921.

Application filed March 24, 1915, Serial No. 16,625. Renewed April 14, 1921. Serial No. 461,367.

To whom it may concern:

Be it known that I, ALEXIS LE BLANC, a citizen of the United States, residing at New York, in the county of New York and State 5 of New York, have invented certain new and useful Improvements in Looms; and I do hereby declare the following to be a full, clear, and exact description of the invention, such as will enable others skilled in the art 10 to which it appertains to make and use the same.

My invention relates to looms. Its object is to provide means for positively and rapidly moving the weft supporting means or 15 shuttle through the shed while at the same time avoiding the warp strands. To this end the invention comprises the combinations and details set forth in the appended claims.

20 I have provided a powerful and simple construction by which the shuttle and the shuttle-carrier run in paths parallel to and on opposite sides of the lower rank of warp strands, the connection between the two 25 traveling with the shuttle and on the same side, without in any way disturbing the warp strands, a feature of especial importance in a machine for weaving wire, for example. By my construction I provide for 30 the use of a large shuttle occupying practically the whole of the vertical space of the shed, and I greatly enhance the certainty and speed of operation, while decreasing the initial cost and operating expenses, especially in machines of the kind for which my 35 device is particularly intended, as herein-after stated.

In the accompanying drawings:—

Figure 1 is a central vertical section 40 through the shuttle carrying mechanism;

Fig. 2 is a partial front elevation;

Fig. 3 is a sectional front elevation;

Fig. 4 is an elevation of the operating mechanism with diagrammatic and sectional 45 detail accompaniments;

Fig. 5 is a detail of the double sheaved pulley of the operating lever;

Fig. 6 is a detail of a part of the rack;

Fig. 7 is a perspective view illustrating 50 the shuttle mechanism in relation to other parts of the loom and in operation;

Fig. 8 is a sectional detail of guiding brackets for the shuttle carrier; and

Fig. 9 is a sectional detail showing the location of the shuttle race-way on the ma- 55

chine and indicating the inclined position it has in practice, the other views for convenience of illustration being vertically arranged with the exception of Fig. 7 which is also inclined as in actual use. 60

In this preferred form of my invention the shuttle is carried positively from side to side and through the shed of the warp strands by a mechanism located beneath the warp strands and which imparts a gradually accelerated movement to the shuttle from the side to the center, gradually decreasing the movement until it comes to rest, thus alternating as the shuttle is carried from side to side in the operation of weaving. 65 70

The shuttle is borne by cupped wheels with cuspidal openings, one being located at each corner of the frame which carries the bobbin, the lips of the cupped wheels turning in arc grooves in the shuttle-carrier thus 75 supporting the bobbin-frame, the wheels traveling in the plane of the lower rank of warp strands. The openings in the wheels turn over each strand in succession so that, as before stated, the shuttle, in effect, passes 80 directly across or through the lower rank of warp strands without touching or disturbing them. 85

In this preferred form I secure the rotation of the cupped wheels which support the 90 bobbin-frame by means of gear-wheels on one end of each shaft which bears the cupped wheels, the gear-wheels engaging a rack-bar as the shuttle is reciprocated so that they are rotated and in turn rotate the cupped 95 wheels as the shuttle is swept across the race-way. Inasmuch as the warp strands lie in different planes as alternate sheds are formed I provide for shifting the rack-bar so that it shall be in coincidence with the 100 location of the lower rank of warp strands at each operation of the shuttle. 105

With my shuttle mechanism as herein set forth I may use a reed in the customary manner between the shuttle and the roll or other device which receives the mesh, or I may dispense with the reed. In the construction illustrated herein I have also provided means for regulating the action of the wire upon the spool or bobbin and details 110 which combine to secure certainty and rapidity of operation.

As illustrated in the drawings, the shuttle is supported from the frame of the machine and in this preferred form rolls back and 110

forth upon the race-way upon roller bearings though it may, of course, be arranged to slide back and forth upon the race-way.

10 represents a standard rail whose foot, in 5 the illustrated form, lies in and is bolted to the inclined post of an intervening member 11 of the frame of the machine, and is a race-way for the shuttle. The standard rail 10 extends transversely across the machine 10 and has mounted on its upper surface a longitudinal beam 12, here illustrated as substantially square in cross section and as having secured on the top a longitudinal flat bar 13. Beneath the bar 13 extend the 15 arms of brackets 131, one at each corner, which serve to keep the shuttle frame in place. A bearing-block 14 straddles the beam 12 and the bar 13 and has journaled in it rollers 15 adapted to travel on the face 20 of the rail 10. Secured to the bearing-frame 14 is a bearing-shoe 16 which, as hereinafter described, is reciprocated back and forth with the bearing-frame 14 carrying with it the shuttle and its parts. In the bearing- 25 shoe 16 are recesses 17 to provide room for the rotation of the rollers 15. At each outer end the bearing-shoe 16 is recessed or grooved as indicated at 18. These arc grooves are the guides and base of what may 30 be termed a floating or shifting bearing for the bobbin-frame.

The body of the frame of the bobbin is illustrated at 19, and in this frame is journaled a spool or bobbin 20. 21 represents 35 wheels journaled on shafts 22, one at each corner of the frame. These wheels 21 have inward circumferential lips 23, each adapted to fit and engage an arc groove 18 in the bearing-shoe 16, so that the bobbin-frame has 40 its weight supported through the guiding and supporting wheels on the curved surfaces of these grooves. The wheels are also cut out as indicated at 24, the openings being preferably, as illustrated, of cuspidal 45 form, this form being adapted to conform to the apparent path described by each stationary warp strand as these wheels run forward across the plane of the warp strands receiving in the openings successive strands. 50 At one end of each of the shafts 22 is a gear-wheel 25 with compound cycloidal teeth formed in the familiar manner. The gear-wheels engage a rack-bar 26 having secured to it a side-bar 27 supported on a bar 55 28 secured in turn to a bracket 29 fastened to the T-rail 10. The shuttle, 19-20, then, is guided by the wheels 21 and 25 and these parts move with the shuttle-carrier 14-16, the teeth of the wheels 21 projecting between 60 strands of the lower rank. A bolt 30 passes through a slot 31 in the bar 27 permitting a sliding movement of the rack-bar 26 so that its pockets which receive the teeth of the gear-wheel 25 may be shifted as the lower 65 ranks of the warp strands change. That is

to say, in one movement of the harness one rank of warp strands will be brought to a certain position. When the next shed is formed the adjacent rank of warp strands will be brought to a position which will be 70 a little to one side of the position of the preceding warp strands. It is this change of the planes of the warp strands which is followed by the adjustment of the rack bar so that as the cupped wheels and rack-wheels 75 rotate the strands may lie substantially in the radial center of the successive openings. The reciprocation of the rack-bar is accomplished by means of a lever 32 pivoted to the frame of the machine at 33 and having its 80 upper rounded end working within a socket member secured to the rack-bar 26. The lower end of the lever 32 is forked as shown at 34 and the fork straddles a shaft 35 carried by the machine frame and driven in an obvious manner by the customary mechanism of the machine. The shaft 35 carries a cam-member 36 which revolves at a predetermined point so as to oscillate the lever 32 and thereby give a slight reciprocating movement, as before described, to the rack-bar 26. 85

It is obvious that the shuttle may be reciprocated by various mechanisms but I prefer a mechanism which I have here illustrated because it gives precisely the desired 90 motion to the shuttle and operates advantageously beneath the warp strands.

A wire cable 37 has its opposite ends secured to opposite ends of the shuttle carrier. The cable then passes over a pulley 38 at 100 one end, and a pulley 39 at the other end, thence from one direction half around one division of a double sheaved pulley 40 to a spring connection 41 and from the other direction half around the other member of 105 the doubled sheaved pulley to an opposite spring connection 42. The pulley 40 is carried on the free end of an arm 43, pivoted at 430, which bears substantially centrally a slot or a slotted reinforcement 44 in which 110 takes a pin on the end of a lever 45, pivoted at 46, and driven by a pitman 47 connected with a crank-arm 48. The movement of the pulley 40 is just one-half the movement of the shuttle. The shuttle travels the full 115 width of the machine and consequently at an average speed twice that of the pulley 40. Furthermore, in accordance with the principles which govern the operation of this form of power transmitting device, the shuttle 120 will start slowly and gradually increase its speed to the center and then decrease in speed gradually till it comes to rest at the other end.

I have provided also for controlling the 125 feed of the weft strand from the spool and its feed from the shuttle after it leaves the spool. It is necessary to keep taut the strands on the bobbin to eliminate any jerk at the end of a stroke. To this end I have 130

provided on the end of the shaft carrying the spool, another spool 49 which provides a housing for a coil spring 50, one end of which is secured to the spool 49, while the 5 opposite end is secured to the frame of the shuttle. The spring 50 is wound to exert a tension on the bobbin, the spring being in a tightly wound position as the weaving material is unwound. In order 10 that the weft strand may not be unwound from the spool until it is subjected to a determined tension there is provided on the outer side of the spool 49 a friction washer 51 of leather or other material, one side of 15 this washer bearing tightly against the spool 49 while a clamping washer or nut 52 bears against the opposite side. This arrangement permits the bobbin to pay out the weft strand as it travels backward and forward while 20 the spring 50 keeps the strand taut and takes up the slack at each end of the stroke due to the return movement of the shuttle.

As the weft strand leaves the bobbin it passes between grooved guide rollers 53 25 which are carried by a sliding frame 54 located upon the frame of the shuttle and having extending outward rods 55 passing through bearings 56 on the shuttle frame, and having interposed between the bearings 30 and the pulley frame a coil spring 57. This spring serves to take up the shock incident to the sudden return movement of the shuttle as it operates forward and backward across the machine.

35 My invention while having a broad range is especially adapted to be used instead of the shuttle mechanism illustrated in the application of F. Nossagk, Serial No. 846,408, filed June 20, 1914, and assigned to the Composite Metal Lath Company of New York, N. Y.

In that machine the wires are woven in a quadrangular mesh and this mesh is taken by the press rolls and conjunctive mechanism, brought to a precise unit, and given a coating of clay or other material, the thus coated article being treated in various ways to complete it ready for burning in an oven to produce the finished product with buttons 50 of clay or patterned brick at the intersecting points.

In Fig. 7 the parts are shown assembled and in operation in that machine. The harness is shown at 58, the toothed guide plate 55 through which the lower rank of warp strands pass at 59, the reed at 60 and the toothed wheel which receives the strands from the shuttle and holds the loops of the selvage while the strands are being carried 60 backward and forward and made into a quadrangular mesh at 61. I have also indicated the various wires, the warp wires in this case being shown by straight lines. The incidental features which appear in connection 65 with this illustration are not necessary

to further describe, it being intended merely to indicate thus the well understood relation which these parts have in such a loom.

In Figs. 2 and 3 I have shown the alternating relation of the warp strands indicating the upper rank above the figure and using arrows to show the direction which will be taken by those strands on the next operation. It will be observed that the upper rank alternates with the lower rank 75 which would necessarily follow from the operation of a harness as illustrated in Fig. 7.

Also, in Fig. 1, I have shown the relation of the shed to the shuttle-frame, there indicating the ranks of warp strands by means of dot and dash lines. It will be observed that the lower rank of strands is shown as passing above the shuttle-carrier and the roller-frame, through the cupped wheels of 80 the bobbin-frame, and beneath the bobbin. This figure also indicates the possibility of this construction in which the bobbin fills practically the whole of the space of the shed permitting the use of a large bobbin 85 carrying a great quantity of weaving material.

In Fig. 3, also, is clearly indicated the manner in which the cupped wheels travel across the plane of the lower rank of warp 95 strands and the manner in which the gear-wheels engage the rack-bar and at the same time pass through the lower rank of warp strands without touching them. This figure also illustrates the relation of the two ranks 100 of strands and the recesses of the rack-bar, and the relation of the shifting mechanism to the relative positions of the ranks of warp strands.

In Fig. 7 is shown in illustrative form 105 the relation of these parts to the various strands in actual operation, the opening of of a wheel having just left one warp strand encircling the next and the weft wire beginning to pay out to the adjacent tooth of 110 the wheel 61, from which it will slip to the next tooth to the rear to be then fed off the press-rolls of the lath-making machine or to a reel or other structure in accordance with the class of machines in which this mechanism may be used.

In my loom thus described it is apparent that the shuttle is carried positively completely through the shed at each operation and that the shuttle while crossing the shed 120 always bears a definite relation to the warps, rendering the beating of the warps impossible until the shuttle has completed its travel.

My mechanism enables me to give practically unlimited shuttle travel and to secure a high speed because the strands do not touch any part of the shuttle during its travel across the shed. In fact, the speed of operation is limited only by the weight of 125 130

the parts which are operated. I am enabled also with this simple construction to give the shuttle a rugged character permitting of high speed and certainty of operation. The 5 entire support of the shuttle being below the plane of the lower rank of warp strands permits the use of a bobbin whose diameter is nearly as great as that of the shed and the bobbin can be made as long as desired with- 10 in practical limits so that I am enabled to use great quantities of weaving material on a single bobbin. By arranging and timing the guiding wheels of the shuttle so that spaces are provided for only one set of warp 15 strands at one stroke of the shuttle and by means of the short movement which re-times the guiding and supporting cupped wheels for the other set of warps on the return stroke I make possible the use of larger 20 bearing surfaces of the wearing parts of the shuttle members, besides providing for a large range in the sizes of the warp strands and in the mesh of the product.

I have used the term "wheels" to designate 25 the parts 21, because it is a convenient term to designate a moving supporting connection between the shuttle and the shuttle-carrier.

Having fully described my invention, I 30 claim:—

1. In a loom, the combination of a shuttle, a shuttle-carrier and wheels carried by and supporting the shuttle and having members projecting between strands of the lower 35 rank, the shuttle and the wheels traveling on one side of the lower rank of warp strands, the shuttle-carrier traveling on the other side.

2. In a wire-weaving loom, a shuttle and 40 shuttle-carrier, means for carrying the shuttle and shuttle-carrier to and fro and means for relatively positioning the shuttle-carrier and the lower rank of warp strands between strokes.

45 3. In a wire-weaving loom, a shuttle having bearing and operating means adapted to straddle each lower warp strand in succession, and means for maintaining a uniform relation of the shuttle bearing and operating means with reference to the position of the lower warp strands in each traverse of the shuttle.

4. In a loom, a shuttle comprising guiding wheels having recesses arranged with 55 reference to the position of the strands of the lower rank of the warp strands, and means for re-timing the wheels so that they will turn over the succeeding rank of warp strands on the return movement.

60 5. In a loom, the combination with a shuttle-carrier having arc-shaped grooves at each end, of a bobbin-frame carrying cupped wheels at each end, the lips of the wheels turning in the arc-shaped grooves to hold the bobbin-frame in position, and means

for positively reciprocating the shuttle-frame and means for rotating the cupped wheels.

6. In a loom, the combination with a shuttle-carrier having curved grooves, a 70 bobbin-frame, guiding and supporting wheels carrying the bobbin-frame and turning upon the curved surfaces of the shuttle-carrier.

7. In a loom, the combination with a race-way, of a grooved shuttle-carrier having roller bearings traveling on the race-way, cupped wheels engaging the grooves in the shuttle-carrier, and means for positively reciprocating the shuttle-carrier. 75

8. In a loom, the combination of a shuttle, cupped guiding and supporting wheels carrying a bobbin-frame on the shuttle, a shuttle carrier, arc grooves in the shuttle-carrier with which the lips of the guiding 85 wheels engage, and means for rotating the supporting wheels when the shuttle is operated.

9. In a loom, the combination of a bobbin, a frame carrying the bobbin, a shaft at each 90 end of the frame, cupped wheels borne by the shafts, grooves in the base of the frame which the wheels engage, a gear-wheel on one end of each shaft and a rack-bar for receiving the rack-wheels, and means for reciprocating the bobbin-frame.

10. In a loom, a shuttle, means for positively operating the shuttle, a race-way on which the shuttle travels, a rack-bar, a gear-wheel on the shuttle for engaging the rack-bar and means for shifting the rack-bar at each reciprocation of the shuttle. 100

11. In a loom, the combination of a shuttle and a race-way, a rack-bar carried by the race-way and having its teeth arranged in 105 accordance with the distance between the warp strands, means carried by the shuttle for engaging the rack-bar, and means for relatively shifting the rack-bar as the warp strands change in the alternate action of the 110 harness.

12. In a loom, the combination of a shuttle, a race-way, a rack-bar on the race-way, shafts at each end of the shuttle and a gear-wheel secured to the shaft and engaging the 115 rack, and wheels borne by the shafts, the wheels having openings to encircle successive warp strands, the openings conforming to the apparent path of the warp strands as the wheels rotate across the line of 120 strands.

13. In a loom, a shuttle comprising in combination, shuttle-carrier having grooves, means for positively reciprocating the shuttle-carrier, a bobbin-frame, shafts at 125 each end of the frame, cupped wheels at each end of the shafts and engaging the grooves in the shuttle-carrier, a gear-wheel at one end of each shaft and a rack-bar with which the gear-wheel engages so that upon 130

- the operation of the shuttle the cupped wheels will be rotated.
14. In a loom, the combination of a race-way, a shuttle-carrier having rollers traveling on the race-way and lying below the plane of the lower rank of warp strands, and a bobbin-frame carried by guiding and supporting wheels which engage grooves in the shuttle-carrier, means for positively operating the shuttle, and means for rotating the guiding and supporting wheels.
15. In a loom, the combination of a shuttle having a bobbin-frame, and means carried by the bobbin-frame for passing across the lower rank of warp strands without touching them, comprising rack-wheels, a rack to be engaged by the rack-wheels and having a slotted connection with the race-way and means for automatically reciprocating the rack to shift its position at the end of each reciprocation of the shuttle.
16. In a loom, the combination of a shuttle-carrier, a bobbin-frame bearing cupped wheels in engagement with the shuttle-carrier, the wheels having openings arranged with reference to the arrangement of the warp strands, and means for moving the shuttle across the plane of the warp strands so that the openings of the wheels receive the successive warp strands.
17. In a loom, the combination with a shuttle-carrier and means for positively operating the shuttle, of a race-way, a rack borne by the race-way, guiding and supporting cupped wheels, rack wheels operating in the rack to rotate the cupped wheels, the cupped wheels having openings, the rack, the rack wheels and the openings of the cupped wheels all being arranged with reference to the positions of the several warp strands.
18. In a loom comprising a shuttle, means for positively driving the shuttle through the lower rank of warp strands of a shed and means for returning it through the succeeding rank of warp strands, and means for placing the shuttle in the same relation to the succeeding rank of strands that it had to the preceding rank, so that the shuttle passes through in each direction without touching any of the strands in either reciprocation.
- In testimony whereof I have hereunto signed my name.

ALEXIS LE BLANC.
